US00D907355S

(12) **United States Design Patent** (10) Patent No.: **US D907,355 S**
(45) Date of Patent: ** *Jan. 12, 2021

(54) **UMBRELLA WITH SOLAR PANELS**

(71) Applicant: **ZON**, El Segundo, CA (US)

(72) Inventors: **Sarah Akin**, Manhattan Beach, CA (US); **David Johnson**, San Francisco, CA (US)

(73) Assignee: **ZON**, Redondo Beach, CA (US)

(*) Notice: This patent is subject to a terminal disclaimer.

(**) Term: **15 Years**

(21) Appl. No.: **29/691,219**

(22) Filed: **May 14, 2019**

Related U.S. Application Data

(63) Continuation of application No. 29/583,773, filed on Nov. 8, 2016, now Pat. No. Des. 848,140, which is a continuation of application No. 29/499,274, filed on Aug. 13, 2014, now Pat. No. Des. 770,757, which is a continuation of application No. 29/487,288, filed on Apr. 7, 2014, now Pat. No. Des. 770,756.

CLAIM

The ornamental design for an umbrella with solar panels, as shown and described.

DESCRIPTION

FIG. 1 shows a perspective view of an umbrella with solar panels;

FIG. 2 shows a top view thereof;

FIG. 3 shows a side view thereof; and,

FIG. 4 shows a side view of the umbrella with solar panels, shown in a closed position.

The broken line showing is included for the purpose of illustrating environment and forms no part of the claimed design. The gray shading in the figures is surface shading that indicates claimed subject matter. The broken lines and unshaded surfaces form no part of the claimed design.

1 Claim, 4 Drawing Sheets
